UNITED STATES PATENT OFFICE.

CHARLES LESLIE NEWLAND, OF LONDON, ENGLAND.

SOUND RECORDING AND REPRODUCING INSTRUMENT.

Application filed August 14, 1922. Serial No. 581,884.

To all whom it may concern:

Be it known that I, CHARLES LESLIE NEWLAND, a subject of the King of England, residing at 223 Westmount Road, Eltham, 5 London, Kingdom of England, have invented certain new and useful Improvements in or Connected with Sound Recording and Reproducing Instruments, of which the following is a specification.

10 This invention relates to sound recording and reproducing instruments.

The invention has for one of its objects to provide this class of instrument with improved control mechanism designed to reduce to a minimum the liability of injury, 15 owing to inattention, to a record and to the reproducer particularly when the end of a record has been reached.

Another object of the invention is to provide the instrument with an improved form 20 of tone-arm, whereby the sound waves from the different sound chambers are kept separate from one another as they enter and pass through said tone-arm thus preventing said 25 sound waves intermingling, and ensuring that the base tones and the higher tones are reproduced quite clear and distinct.

The invention refers primarily to starting 30 and stopping control mechanism of the kind whereby the instrument is stopped, and the needle or stylus is simultaneously raised from the record, by hand actuated means operable from the exterior of the cabinet or case of the instrument, and without the necessity of 35 opening said cabinet or case, and of lifting the needle or stylus from the record directly by hand. The invention also refers to instruments of the kind in which two or more separate reproducers or sound boxes, each having a sound chamber, or a single body internally partitioned to form two or more 40 separate and independent sound chambers, are or is carried by the end of a tone-arm.

45 According to one feature of the present invention starting and stopping mechanism of the kind referred to is provided with a starting member which cannot be operated, to start the instrument, when the cabinet or case is closed and until said cabinet or case 50 is opened for the purpose of using the instrument.

Another feature of the invention consists in that a single tone-arm is provided and

formed with two or more spaced tubes or 55 branches which are separate and distinct from one another along their lengths, are mounted on a single pivot common to them both or all, and are independently connected to the separate sound chambers and do not join with or merge into one another except at the point at their ends where they are pivoted and the sound waves enter the trumpet or horn or the sound diffusing 60 chamber of the cabinet or box of said instrument. Thus, the invention is distinguished 65 from the types of instrument in which two or more separate and independently pivoted tone-arms, or a single internally and longitudinally partitioned tone-arm having its 70 extreme end bifurcated, are or is employed.

The invention will now be described with reference to the accompanying drawings, in which:—

Figure 1 is a longitudinal sectional elevation illustrating a suitable manner of carrying out the invention in connection with a gramophone, and indicating the mechanism in position after having stopped the instrument, 75

Figure 2 is a view similar to Figure 1 and indicating the mechanism in position after having started the instrument, 80

Figure 3 is a rear elevation showing the starting lever in position when the instrument is stopped, 85

Figure 4 is a view similar to Figure 3 and indicating the starting lever in position when the instrument has been started, and

Figure 5 is a perspective view, with parts broken away, of the instrument complete; 90

Figure 6 is a longitudinal sectional elevation illustrating a modified manner of carrying out the invention, and indicating the mechanism in position whilst the instrument 95 is running.

Figure 7 is a plan of parts of the mechanism shown in Figure 6,

Figure 8 is a sectional elevation on the line 8—8 of Figure 7, and

Figure 9 is a rear elevation showing the starting lever in position when the instrument is running; 100

Figure 10 is a plan illustrating a suitable construction of a two-part tone-arm,

Figure 11 is an underneath plan of the inner end portion of the tone arm of Figure 105

10 and showing the securing flange turned round a little in relation to said tone-arm, and

5 Figure 12 is a detail sectional elevation on the line 12—12 of Figure 10;

Figure 13 is a sectional elevation of a modified form of two-part tone-arm;

Figure 14 is a perspective view illustrating yet another modification, and showing 10 the invention as carried out in connection with a three-part tone-arm,

Figure 15 is a view of the inner end of the tone-arm of Figure 14, and

15 Figure 16 is a detail sectional elevation on the line 16—16 of Figure 14;

Figure 17 is a detail plan of still another modification.

Similar parts in all of the figures are designated by like reference numerals.

20 The mechanism shown in Figures 1 to 5 comprises a rod 15 mounted to slide axially through the front 16 of the cabinet or case of the instrument, and formed at its outer end with a finger knob 17 and at its inner 25 end with a collar 18. A lever 19 is pivoted intermediate its ends at 20 on the inside of the front of the cabinet or case, and is provided with an enlargement 21 adapted to cooperate with the rod and its collar, and is 30 connected to a spring 22 which tends to maintain said enlargement in contact with said rod and collar. A bar 23 mounted to slide longitudinally and in the vertical plane of the rod 15 has its front end arranged adjacent to a shoulder 24 provided on a rocking bar 25 the upper end of which contacts with the collar 18 on said rod, whilst its lower end is loosely mounted on a screw and has a spring 26 pressing against it. The 35 rear end of the bar 23 is slotted to receive the lower end of a finger 27 which is pivoted intermediate its ends at 28, and is curved over at its upper end 29. The bar 25 carries a 40 brake block 30 of fibre or other suitable material. A spring 31 is connected to the lower end of the finger 27 and tends to pull the bar 23 forwardly and the finger into the position indicated in Figure 2. The reproducer 32 of the instrument is mounted to 45 turn on the forward end of the tone arm 33, trumpet or horn of the latter, and a curved plate 34 or other member is connected to said reproducer and serves as a crank-arm by medium of which the latter is lifted and 50 as a partial counter-balance weight for the same.

55 The mechanism above described operates as follows:—Normally, that is, when the instrument is not working, Figures 1, 3 and 60 5, the rod 15 is extended inwards within the cabinet or case and, through the medium of the bar 23 operatively connected to its inner end by the bar 25, holds the finger 27 in such position that the upper end of said finger is pressed upon the curved plate 34

and thus holds the reproducer 32 in a raised position and with its needle or stylus 35 lifted out of contact with the record 36 on the turntable 37 of the instrument; the brake block 30 is held in contact with the turntable and prevents rotation of the latter. At the same time the enlargement 21 on the lever 19 is held by its spring in front of the collar 18 on the rod 15, so that, until said lever is moved out of this position, said rod is locked and cannot be pulled forward; if the cover or lid 38 of the cabinet or case is closed as shown, the lever 19 cannot be operated to release the rod 15, and to start the instrument.

80 Now, assuming that the cover or lid 38 of the cabinet or case has been opened, if the lever 19 is turned over on its pivot to release its enlargement 21 from the rod 15 the latter is immediately and automatically moved 85 forwardly, to extend out of the front of said cabinet or case, by means of the bar 23 through the bar 25, which bar 23 is pulled forward by the spring 31. This forward movement of the bars 23 and 25 turns the 90 finger 27 on its pivot and moves the brake block 30 out of contact with the turntable 37, which now starts to rotate, and the upper end 29 of said finger retracts from the curved plate 34; this release of the curved 95 plate enables the reproducer 32 to turn and its needle or stylus 35 to engage the record 36, and it is preferred that said movement of the reproducer is brought about by hand to prevent bumping of the needle or stylus 100 on to the record. The lever 19 then rests on the periphery of the collar 18, Figures 2 and 4.

105 Reversely, when it is desired to stop the instrument the rod 15 is pressed inwards and said rod pushes the bar 23 back through the bar 25, the starting lever 19, in the meantime, springing into engagement in front of the cooperating collar 18 on said rod. This movement of the bar 23 swings the finger 27 110 into its normal position so that its upper end 29 first engages with the curved plate 34 to raise the reproducer 32 and lift the needle or stylus 35 out of contact with the record 36, and then the brake block 30 engages with the 115 turntable 37 and stops the latter. The starting lever 19 cannot return to its normal position until the stopping rod 15 is pressed inward.

120 In this manner the needle or stylus 35 is lifted and the instrument is stopped in one operation, and this without the necessity of opening the cabinet or case and fumbling with the reproducer 32 by hand; the starting lever 19 cannot be operated if the cabinet 125 or case is closed and locked, and the stopping rod 15 cannot be pulled out; and the curved plate 34 serves to partially counter-balance the weight of the reproducer, to reduce to a minimum the pressure of the needle or 130

stylus 35 upon the record 36, and as means for lifting said needle or stylus away from the record.

If desired, and in another modification, 5 means may be provided whereby the mechanism is operated automatically to stop the instrument when the end of the record is reached. For instance, the slidable bar 23 of Figures 1 to 5 could be adapted to be 10 moved to its stopping position by a pivoted lever which is directly contacted and operated by the needle or stylus 35, by the sound-box of the reproducer 32, by the tone arm 33, or by any other suitable movable part carried by said reproducer or tone-arm, at the 15 moment when the record 36 is finished. The pivoted lever may be operatively connected to an india-rubber or other D shaped pivoted block which is turned into contact with the 20 turn-table 37. Thus, in the construction illustrated in Figures 6 to 9 a spindle 40 is rotatably mounted on the lid or cover 38^a and carries an india-rubber or other fairly soft D shaped block 41, and at its lower end 25 a fibre or other cam 42. The upper end of the spindle 40 also carries an arm or lever 43 which is adjustable longitudinally and is held in place by a finger screw 44, the free end of said arm being adapted to be contacted 30 by the crank-arm 34. A slidable bar 23 is operatively connected to a pivoted finger 27 at its rear end as before, and at its front end to a stopping rod 15^a by means of a hole in said bar engaging over a pin 45 on a 35 bracket piece 46 carried by said rod. A starting lever 19^a pivoted at its lower end at 20^a is formed with an enlargement 21^a adapted to engage in front of the bracket piece 46 when the instrument is stopped, 40 and to rest against said bracket piece, Figures 6 and 9, when the instrument is running. The starting lever 19^a carries a wedge-shaped brake block 30^a which is always in close proximity to the edge of the 45 turntable so that a comparatively small movement of the lever 19^a, which moves the enlargement 21^a behind the bracket piece 46 but is not sufficient to bring the lever against the rod 15^a, causes the block 30^a to engage the 50 edge of the turntable and stop its movement. The cam 42 is adapted to engage a lever 47 pivoted at 48 and arranged to press against a pin 49 depending from the slidable bar 23. 55 With this construction, the automatic stopping mechanism is "set" before the record is started, and this by swinging the tone arm 33 over the record until the needle or stylus 35 is over the last groove 36^a of said record, as indicated in Figure 7, and by adjusting 60 the rod 43 until its free end just touches the adjacent end of the crank arm 34. When so adjusted the rod is in its "off" position and the block 41 is just clear of the turn-table. The tone arm 33 is then swung back 65 to position the needle or stylus 35 at the com-

mencement of the record, and the instrument is started by turning over the lever 19^a and causing the stopping rod 15^a and slidable bar 23 to move forwardly, and the finger 27 to free the crank-arm 34 in the manner described in connection with Figures 1 to 5. Now, when the end of the record is reached, and the crank-arm 34 again arrives at the position indicated in Figure 7, said arm engages the rod 43 and moves the latter in the 70 direction shown by the arrow, thus rotating the spindle 40. The rotation of the spindle 40 turns the block 41 into contact with the rotating turntable 37, and in this manner said spindle is further rotated sharply and 75 decisively. The sharp movement of the spindle 40 causes the cam 42 to press the lever 47 smartly backwards, and said lever to also press the bar 23 rearwardly by medium of the pin 49, so that the reproducer is lifted 80 by the engagement of the finger 27 with the plate 34. At the same time, the rearward movement of the bar 23 pulls the bracket piece 46 away from the starting lever 19^a and allows the latter to spring into 85 position in front of the said bracket piece, so that the brake block 30^a is moved into engagement with the turntable 37 to stop the instrument. The wedge shape of the brake block 30^a causes the turntable to assist in 90 moving the lever 19^a into position in front of the bracket piece 46. It will be noticed that with the construction of the mechanism described in connection with Figures 6 to 9 the 95 instrument can be stopped either by hand or automatically according to requirements, and that the particular parts of the mechanism for these two operations are automatically "set" when the starting lever 19^a is operated 100 to start the instrument. 105

As shown particularly in Figures 1, 5, 10 and 11 the tone-arm 33 may be formed by two tubes or branches 50, 50, which are connected to and merge into one another only at the elbow or base portion 51 of said tone-arm, that is, at the part of the latter where it is connected to the trumpet or horn 52 or to the chamber or box of the cabinet of the instrument. The two tubes may first be made separately from one another and then be soldered or otherwise secured together at their base ends 53, or they can be cast or otherwise formed integrally with each other at said base ends as in Figures 1, 5, 10 and 11. The portions or ends 53 of the two tubes where the latter join one another together form the elbow or base of the tone arm, and this elbow or base can be externally cylindrical and be pivotally seated within a 115 socket secured on the cabinet or box of the instrument in known or convenient manner. The centre of the elbow or base can be provided with a perforated boss to receive a pivot pin 54 and with a comparatively thin partition as at 55. In the construction 120 125 130

shown in Figures 1, 5, 10 and 11 the tubes merge into and are connected to one another by means of a base plate 56 which is rotatably mounted in a flanged ring 57 secured on 5 the cabinet or box and provided with a bridge piece 58 carrying the pivot pin 54.

The above references to the raising of the reproducer are meant to include many constructions of instruments in which said 10 reproducer is carried by one end or both ends of a U or other shaped connecting tube 59 one end 60 of which is pivoted to the adjacent end of the tone-arm 33, trumpet or horn at 61 so that said connecting tube and the 15 reproducer can be turned over or lifted upon said tone-arm, trumpet or horn. The invention is equally applicable to instruments having a single sound box or chamber and to those having two or more sound boxes or 20 chambers. Again, the connecting tube 59 could be dispensed with and the reproducer can be adapted to rotate or turn on its own axis and upon the end of the tone-arm, trumpet or horn. When the tone-arm is provided with two or more branches the reproducer or reproducers, sound box or boxes is or are fastened to and carried by the free 25 ends of said branches or tubes 50 of the tone-arm in any suitable manner, and so that the 30 separate outlets leading from the several sound chambers of the reproducer, reproducers, sound box or boxes are independently connected to said tone-arm. Thus, in the case of two reproducers or sound boxes, 32, 35 32^a Figures 10 and 12, the outlet of each of the latter may be mounted within or upon one of the ends of the U-shaped connecting tube 59, the arm 60 of said tube being rotatably carried within two sleeves 62 provided 40 on the ends of the two tubes forming the tone-arm, so that said connecting tube and the reproducer, reproducers, sound box or boxes can be turned over or lifted on said tone-arm in known manner. The pivoted 45 arm 60 of the connecting tube is removably retained in place within the sleeves of the tone arm preferably by means of a collar 63 mounted on and detachably secured to said pivoted arm and interposed between said 50 sleeves, said collar serving also to prevent lateral movement of the connecting tube. The connecting tube preferably tapers and increases in diameter from its outer or free end towards the portion of said tube pivoted within the sleeves of the tone-arm, and 55 this so that the tube conforms to the general shape or increasing diameter of the tubes 50 forming said tone-arm. The pivoted arm of the connecting tube is formed with apertures such as 64 leading into the tubes of the tone arm, a partition block or disc 65 being disposed between the sleeves 62.

In a modification, Figure 13, three reproducers or sound boxes, 32, 32^a and 32^b may 60 be employed, in which case the third repro-

ducer or sound box 32^b can be connected by a small tube 65 to the collar 63 above mentioned, the sound waves from this third unit passing through said collar through an aperture 66 provided therein, and through two 70 apertures 67 provided in the U-shaped connecting tube into both of the tubes 50 forming the tone-arm. The small tube 65 may be made separately from and secured to the collar 63 or be formed integrally therewith. 75 In the construction illustrated in Figures 14 to 16 the small tube 65^a is secured to the pivoted arm 60 of the U-shaped connecting tube 59, and its inner end is adapted to move in a slot 68 formed between the two 80 sleeves 62, 62. The tube portion 60 is formed with apertures 64 as before, and with a third aperture 64^a through which the tube 65^a communicates with the central tube 50, partitions being provided within said tube portion and between said apertures 64 and 64^a.

Figures 14 to 16 also illustrate a tone-arm built up of three tubes or branches 50; having their inner or base ends 53 merging into 90 and secured to one another by means of a semi-cylindrical box 56^a pivoted at 54^a, 54^a to a flange 57^a which is fastened over an opening 69 formed in the cabinet or case of the instrument, such as at the back 95 thereof.

In further modified arrangements the U-shaped connecting tube may be disposed with its base portion 59^a rotatably mounted within the sleeves 62 on the tone-arm, or said tube can be substituted by two separate elbow-pieces such as 59^b, Figure 17, each having one of its ends mounted to turn in one of the sleeves. 100

The collar 63 may be formed integrally with the plate 34 as indicated in Figure 2. The means for mounting the reproducer or reproducers, sound box or boxes on the tone-arm may be modified. 105

If desired the mechanism may be modified in any suitable manner to enable the brake block to engage with the governor disc of the clockwork or other motor of the instrument, or with any other movable part of the motor or of the transmission between the latter and the turn-table or support 37 of the record 36, said movable part being, however, distinct from said turntable or support. 110

What I claim is:—

1. In a device of the class described, the combination of a pivotally mounted sound box having a combined crank arm and counterbalance depending therefrom at one side of its pivot, a pivoted lever having one end movable into contact with said crank arm to raise the sound box about its pivot, a spring normally holding the lever out of contact with the crank arm, and reciprocable means connected with the lever and 125

operable to move the lever in opposition to said spring and raise the sound box.

2. In a device of the character described, the combination of a cabinet, a tone arm within the cabinet and having a sound box, a lever pivoted adjacent the tone arm and movable into contact with the sound box to raise the same, means normally holding the lever out of contact with the sound box, a slide connected with the lever and extending to the front part of the cabinet, and means operable from without the cabinet to move said slide and lever and raise the sound box.
- 10 3. In a device of the character described, the combination of a cabinet, a tone arm within the cabinet and having a sound box, a combined crank arm and counter-balance connected with the sound box, a lever pivoted beneath the tone arm and movable into contact with the crank arm to raise the sound box, a spring normally holding the
- 20

lever out of contact with the crank arm, a slide connected with the lever and extending to the front part of the cabinet, and means operable from without the cabinet to move said slide and lever and raise the sound box.

25 4. In a device of the character described, the combination of a cabinet, a sound reproducer pivotally mounted within the cabinet, a lever movable into contact with the reproducer to swing the same away from the record, a plunger operatively connected to the lever and operable from the exterior of the cabinet to raise the reproducer, and a spring-held latch pivoted to the inside wall of the cabinet and automatically operable to latch said plunger when the latter is moved to raise the reproducer.

30 35 In testimony whereof I have hereunto signed my name.

CHARLES LESLIE NEWLAND.
